TAP RECONDITIONING MACHINE

Sven B. Hellstrom, Grosse Pointe Farms, Mich.,
assignor to Detroit Tap & Tool Company, De-
troit, Mich., a corporation of Delaware

Application May 20, 1942, Serial No. 443,818

5 Claims. (Cl. 51—98)

This invention relates to tap reconditioning machines.

It is a primary object of the present invention to provide a simple, compact, and yet at the same time precise and accurate machine capable of performing all of the necessary operations required to recondition taps after the same have become worn as a result of use.

Still further, it is an object of the present invention to provide a tap reconditioning machine which is capable of performing the desired grinding and finishing operations necessary to recondition taps upon taps which may vary widely in size, number of flutes, angle of taper, and degree of chamfer.

Still further, the invention contemplates the provision of apparatus which may easily and conveniently be adjusted to accommodate taps having various numbers of flutes and taps which are designed for either right or lefthand threads.

Still further, the invention contemplates the provision of apparatus which is sufficiently simple in construction so that the same may be operated by relatively unskilled labor.

Many other and further objects, advantages, and features of the present invention will become apparent from the following description, when considered in conjunction with the accompanying drawings, wherein:

Figure 1 is a top plan view with parts in section showing one form of apparatus embodying the improvements of the present invention.

Figure 2 is a front elevational view of the apparatus shown in Figure 1 with parts broken away and parts in section to illustrate more fully and clearly the construction and arrangement of parts.

Figure 3 is an end elevational view of the apparatus shown in Figures 1 and 2 taken from the righthand end of the apparatus as shown in these figures.

Figure 4 is a fragmentary elevational view showing the main grinding wheel and the apparatus for truing the same.

Figure 5 is an end elevational view taken along line 5—5 of Figure 2 with parts in section showing the head assembly for holding a tap while the chamfer is ground thereon.

Figure 6 is an end elevational view taken along the line 6—6 of Figure 1 showing in further detail the head assembly for holding a tap while the chamfer is ground thereon.

With more particular reference to the drawings, it must be borne in mind that the drawings disclose but one single embodiment of the inven-

tion described and claimed herein and, while the construction shown is quite specific, many modifications thereof and departures therefrom may be made without departing from the generic spirit or scope of the invention as defined in the appended claims.

In the specific embodiment of the invention illustrated in the drawings, the apparatus shown comprises a base 10 which is preferably formed from a single, integral hollow casting and which serves to provide a rigid support for the tap reconditioning apparatus hereinafter described in detail.

As will hereinafter be more clearly brought out, 15 certain portions of the apparatus are preferably mounted interiorly of the base 10. This base member 10 may obviously be mounted upon or include a pedestal (not shown) if it is desired to support the apparatus directly on the floor 20 of the shop. On the upper surface of the base 10, a motor support 11 is mounted adjacent one end of the base member. An electric motor 12 is rigidly anchored to the motor support by means of screws 13, as shown in Figure 2, and, as seen 25 in Figure 5, the motor may be conveniently supplied with electric current from a suitable flexible conduit 14.

The motor support 11 is slidably mounted on the base 10 by means of ways 15 which serve 30 to permit transverse sliding movement of the motor support and the motor carried thereby with respect to the base member. This sliding movement, it will be noted, is in a direction perpendicular to the axis of rotation of the motor. 35 Consequently, as this sliding movement takes place, the motor support and motor will be bodily shifted in a direction perpendicular to the axis of the motor.

This sliding movement of the motor is accurately and precisely controlled by means of a feed screw 16 journaled for rotation in a suitable, upwardly projecting boss 17 formed on the base 10. This feed screw 16 is rotatably received by a suitable lead nut anchored to the motor support. The feed screw includes an integrally connected, conveniently accessible handle 18 and it will be clear from the construction which is described that rotation of the handle 18 will serve to cause bodily shifting of the motor support and motor with respect to the base 10.

In order that the motor support and motor may be locked in predetermined, adjusted position when desired, a thumb screw 19, seen in Figure 2, is provided which serves to positively anchor the 55 motor support in predetermined, adjusted posi-

tion with respect to the base when it is desired to retain the motor support fixed in predetermined position. The motor 12 has a shaft projecting from each axial end thereof to permit the mounting of two simultaneously operated abrasive wheels, the construction and function of which is hereinafter described in detail.

At the lefthand side of the apparatus, as seen in Figure 2, a generally cylindrical abrasive wheel 20 is mounted on the shaft of the motor. This 10 abrasive wheel is partially surrounded by a housing 21 which is directly connected to the housing of the motor 12 in order that as movement of the motor takes place, the housing will be bodily moved also. Integrally formed on the 15 housing 21 is a pair of generally cylindrical bosses 22 and 23, the forward boss 22 being clearly seen in Figure 2, while both bosses are clearly shown in Figures 1 and 5. The purpose and function of these bosses 22 and 23 are hereinafter described 20 in detail.

As is clearly seen in Figures 1 and 2, the outer axial end of the housing 20 is closed by means of a removable cover plate 24 secured to the housing by means of screws 25 in order to provide means for gaining access to the housing when it is desired to re-mount or replace the grinding wheel 20 on the shaft of the motor. The manner in which the housing and cover plate are recessed or cut away to give access to the periphery of the abrasive wheel 20 is clearly seen in Figure 4.

Referring specifically now to Figure 4, it will be seen that a simple, convenient and accurate device is provided for truing the surface of the abrasive wheel 20. This device comprises an arm 26 which has permanently and rigidly connected thereto a pivot pin 27 adapted to be received within a hollow bore 28 in the boss 22. The axis of this bore 28, it will be noted, is substantially tangential to the periphery of the grinding wheel. At its outer end, the arm 26 carries an adjustable screw 29 provided with a diamond point adapted to engage the periphery of the grinding wheel and it will be seen that as the arm 26 is swung about the pivot pin 27, the diamond point on the screw 29 will be moved transversely across the surface of the abrasive wheel in order to provide the wheel with a substantially true cylindrical surface and it will be seen that as the wheel becomes worn, the set screw 29 may be adjusted to advance the point thereof generally radially toward the center of the abrasive wheel. When not actually in use, the arm 26 may be mounted in inoperative position out of the way by removing the pin from the bore 28 and inserting the pin in a similar bore 30 formed in the boss 23.

As will hereinafter become more clear, this abrasive wheel 20 is designed and intended for grinding the chamfer on the point of a tap, that is, grinding the conical surface of the land between adjacent flutes in a tap and it will be appreciated that this surface, while generally conical in form, must be eccentric to the axis of the tap in order to provide the necessary relief back of the cutting edge of the tap point. The portion of the apparatus now to be described is that which serves to hold the tap to be ground in predetermined position with respect to the grinding wheel and which serves to permit movement of the tap in such a manner that this chamfer may be accurately and precisely ground to the finally desired form.

Referring now to Figure 2, it will be seen that 75

the base 10 is provided at the forward, lefthand corner thereof with an upwardly extending, generally circular boss 31 which serves to provide means for mounting an outwardly extending bracket 32 which in turn serves to mount the apparatus for holding the tap hereinafter described in detail. As is clearly seen in the drawings, the bracket 32 may be pivotally adjusted with respect to the base 10 and may be anchored in predetermined adjusted position with respect to the base and with respect to the pivot bolt 33.

As is clearly seen in Figure 1, an extending portion of the surface of the boss 31 is provided with graduations generally designated as 34 and it will be readily appreciated that these graduations serve to indicate the angular position of the bracket 32 with respect to the base. The bracket 32 is provided with a longitudinally extending slot which provides means for adjustably mounting a tap holder support 35. As is best seen in Figure 5, the tap holder support 35 is anchored in the desired predetermined adjusted position with respect to the bracket 32 by means of a large manually operated nut 36 threadably received on an externally threaded flanged bushing 37. The flange of this bushing 37 overlies and engages the upper surface of the bracket 32. A washer 38 surrounds the lower end of the bushing 37 adjacent the nut 36 and this washer is interposed between the nut 36 and the underside of the bracket 32. This structure is clearly illustrated in Figure 5. As is seen in Figure 5, the bushing 37 surrounds an internal bushing 39, fixedly anchored to the tap holder support 35 by means of a cap screw 40. The tap holder support 35 has a downwardly extending flange 41 which meets with and slides against an upwardly extending flange 42 formed on the bracket 32, these flanges together serving to preclude any relative, rotative movement between the tap holder support 35 and the bracket 32.

From the foregoing, it is clear that the tap holder support may be adjusted to any desired longitudinal position with respect to the bracket 32 merely by loosening the hand nut 36 and sliding the support to the position desired, then tightening the nut to lock the support in predetermined adjusted position.

The tap holder support is provided at its upper end with a relatively large cylindrical bore therethrough and it is noted that the axis of this bore is directly parallel to the slot in the bracket 32 and inasmuch as the tap to be ground, when mounted in the manner hereinafter described, will be mounted with its axis parallel to the axis of this bore, it is readily appreciated that the scale 34 described above may serve to indicate the conical angle being ground on the point of the tap and it will likewise be seen that this conical angle may be varied as may be required by adjusting the pivotal position of the bracket 32 with respect to the base.

This cylindrical bore through the tap holder support has anchored therein a concentric bearing sleeve 45 in which is rotatably mounted a flanged bushing extending axially throughout the length of the bore. As is clearly seen, this bushing 46 is provided at the forward axial end thereof with a flange 47 which overlies and bears against one axial end of the bore through the tap holder support. At the opposite end, this bushing is externally threaded and surrounded by a collar 48 anchored to the bushing to rotate therewith. The purpose and function of this collar are de-

scribed in detail below. The bushing 46 is locked against axial movement with respect to the tap holder support by means of a lock nut 49 threadably received on the bushing. This lock nut 49 forces the lock washer 48 against the tap holder support sufficiently snugly to preclude any axial movement of the bushing in the bore and yet at the same time permit rotation of the bushing in the bearing sleeve 45.

The bushing 46 has mounted therein a chuck housing 50 which chuck housing is generally cylindrical in form and which, as will hereinafter be more clearly seen, may be concentrically mounted with respect to the bushing. The outside diameter of the chuck housing is, however, considerably smaller than the inside diameter of the bushing 46, thereby providing a clearance, designated as 51, clearly shown in Figure 1 of the drawings. A chuck 52 of conventional construction is rotatably mounted on a suitable bushing 53 interiorly and co-axially of the chuck housing 50. This chuck includes the conventional jaws 54 which may be closed to lock the shank of a tap therein in the conventional manner and it is inherent from the construction which is described that the axis of the tap thus mounted will coincide with the axis of the chuck 52, bearing sleeve 53, chuck housing 50, but will not necessarily coincide with the axis of the bushing 46, bearing sleeve 45, or the bore in the housing 35, due to the mounting of the chuck housing in the bushing 45 in the manner now to be described.

The chuck housing 50 has the inner axial end thereof provided with a flange of substantially the same construction as the flange 47 on the axial end of the bushing 46, and this flange, as is shown in Figure 1, overlies the flange 47 on the bushing 46. The chuck housing 50 is anchored to the flange of the bushing 46 by means of a pivot screw 56, threadably received within the flange 47, and having a plain shank to permit pivotal movement of the chuck housing about the screw to a limited extent. On the diametrically opposite side of the flange of the chuck housing, the flange is slotted to provide an arcuate slot, this slot being formed about an arc whose center coincides with the screw 56. A cap screw 57 passes through this slot and is threadably received in the flange 47 of the bushing 46 in order that the position of the chuck housing may be adjusted and anchored with respect to the bushing 46.

As is clearly seen in Figure 2 of the drawings, the periphery of the flange 47 is provided with a suitable series of graduations 58 which may be read from a line 59 on the periphery of the flange of the chuck housing. These graduations serve to indicate the degree of eccentricity of the chuck and chuck housing with respect to the bushing 46, and it will be readily appreciated that as a result of adjusting the pivotal position of the chuck housing 50 with respect to the screw 56, the amount of eccentricity between the chuck housing and the bushing 46 can be accurately adjusted to the desired amount and the chuck housing can then be anchored in position with respect to the bushing in order to retain the same in predetermined adjusted position.

As will be readily appreciated, the magnitude of this eccentricity determines the magnitude of the back-off or relief produced back of the cutting edge of the tap land being ground and it will be seen that movement of the chuck housing to eccentric position in one direction will

serve to provide the desired back-off angle, relief, or chamfer for righthand taps and adjustment to the desired degree of eccentricity in the opposite direction will serve to produce a similar result in the event lefthand threaded taps are to be ground.

Referring again to Figure 1 of the drawings, it will be seen that the chuck 52 is formed to provide a rearwardly extending cylindrical shank 65 whose axis coincides with the axis of the chuck 52. Keyed to this shank 65 is a drum. Such drum may be a unitary structure or may be a plurality of discs secured together and are axially slideable on the shank 65, but are non-rotatably mounted with respect thereto. The chuck housing 50 includes a radially extending boss 67 adjacent the rear end thereof which serves to mount a bushing 68, providing a cylindrical bore in which is mounted a plunger 69 which is constantly urged radially inwardly by means of a compression coil spring 70.

Adjacent one side of the boss 67 is a pivotally mounted control handle 75 which serves two separate and distinct functions. This handle in the first instance may be pivotally swung about a pivot pin 76 and includes a projecting lug 77 which is received in a complementary recess in the side of the plunger 69 whereby pivotal movement of the handle 75 about its pivot 76 will serve to withdraw the plunger 69 against the force of the spring 70.

The drum 66 at longitudinally spaced regions therealong or each of the discs 66 has a series of equally circumferentially spaced peripheral notches therein and each of these regions or discs has a different number of notches corresponding in number and spacing to the number and spacing of the flutes in the various sizes of taps to be ground on the apparatus herein described.

The drum or the discs which as a group comprise the index drum project outwardly from the rear end of the chuck housing. From the foregoing, it is clear that when a tap is to be ground, the tap may be mounted in the chuck, the handle 75 may be swung about its pivot 76 to withdraw the plunger 69. The projecting end of the index drum then may be withdrawn until the disc having the same number and spacing of notches as the number of spacing of the flutes in the tap is located opposite the plunger 69. The handle 75 may then be swung so that the plunger engages a peripheral notch in this disc. The rotative position of the tap in the chuck may then be adjusted so that proper grinding will result from operation of the apparatus, as hereinafter described.

It will be apparent that movement of the handle 75 arcuately about the axis of the chuck holder will cause rotation of the chuck housing 50 and bushing 46 to which it is anchored. Inasmuch as the engagement of the plunger 69 with one of the discs 66 serves to preclude rotational movement of the chuck with respect to the chuck housing, rotation of the chuck housing and bushing 46 will cause similar rotation of the chuck 52 and the tap mounted therein. However, as explained above, the chuck has its axis slightly offset from the axes of the bushing 46 and bearing 45. Consequently, the rotation of the tap will not be about the axis of the tap, but about the axis of the bushing 46 which is slightly eccentric with respect thereto.

As is most clearly seen in Figure 2, the collar 48 has a flange which overlies the exterior of the support 35 and a portion of this flange is cut

away. The rotation of this assembly just described within the tap holder support 35 will cause rotation of the collar 48 inasmuch as this collar is anchored to the bushing 46. A stop pin 85 projects from the tap holder support and engages the flange on the collar 48, as shown in Figure 2. A plurality of holes 86 are provided in the exterior of the tap holder support, and a removable screw 87 may be inserted in any of these holes as may be desired. This screw is preferably anchored to the tap holder supporting housing by means of a chain 88. The spacing of the holes 86 with respect to the stop pin is precise and insertion of the screw 87 in these holes, together with the stop pin and collar 48, serve to provide means for accurately and precisely controlling the magnitude of the rotative movement of the chuck housing within the tap holder support.

It will be appreciated that the magnitude of the angular movement to which the tap is subjected during the grinding operation will depend upon the number of flutes in the tap. Consequently, the location of the removable screw 87 may serve to adjust the apparatus for use in grinding taps having any desired number of flutes.

In order to completely re-condition taps, it is necessary not only to grind the lands between the flutes, but also to grind the tapered portion of the flutes themselves, this latter operation being known as spiral pointing when carried out in the manner hereinafter described in detail.

Referring now specifically to that portion of the apparatus illustrated in the right hand portion of Figure 2 of the drawings, it will be seen that the shaft 90 of the electric motor 12 has anchored thereto a generally frusto-conical abrasive wheel 91 by means of a conventional nut 92. In much the same manner as at the opposite end of the motor, this abrasive wheel 91 is enclosed within a suitable housing 93 permanently secured to the motor, the open axial end of which housing is closed by means of a suitable cover plate 94 by means of screws 95. As is particularly clearly illustrated in Figure 3 of the drawings, the housing 93 and cover plate 94 are cut away to expose a suitable portion of the periphery of the grinding wheel 92 in order that the grinding operations described below may be carried out.

The peripheral surface of the grinding wheel 91 is dressed by hand in any convenient manner to provide a radius thereon of a curvature approximating the curvature of the flute it is desired to produce in the spiral point of the tap to be ground. Inasmuch as the form of this portion of the flute of the tap is not particularly critical, hand dressing of the abrasive wheel produces a sufficiently close form to produce the results desired in the grinding operation.

Means are provided for precisely, accurately, and positively adjusting the position of the tap to be ground for this spiral pointing operation. This apparatus is best disclosed in Figure 2 of the drawings. In this figure, it is clear that the base 10 may be provided with a second end wall 84, spaced outwardly from the end wall 96 thereof and that these walls 84 and 96 may be rigidly interconnected by means of a suitable web 97. The walls 84 and 96 are provided with axially aligned bores which serve to receive a pin 83, journaled for rotation therein. Wall 84 is provided around the bore with a boss 98 to which is secured a feed nut 99 by means of screws 100.

10 A feed screw 101 having an operating crank 102 attached thereto is threadably received in the feed nut 99 and has its inner end anchored to the pin 83 through a ball bearing assembly 103. It is apparent from this construction that rotation of the crank 102 will serve to accurately and precisely adjust the axial position of the pin 83, but due to the interposition of the raceway 103, the pin 83 is free to rotate independently of the feed screw 101.

15 At its opposite end, the pin 83 may be of reduced diameter and surrounded by a torsion coil spring 105, one end of which is anchored to the pin and the opposite end of which is anchored to the base member. The purpose and function of this coil spring will become clear as the description of this portion of the apparatus proceeds.

20 Permanently anchored to the pin substantially centrally between the walls 84 and 96 is a housing 110 which is locked to the pin by means of a set screw 111. This housing 110 threadably receives an adjusting screw 112, the upper end of which is provided with a handle 113. The screw 112 is received in an internally threaded bore 114 in the housing 110 and this housing also includes two smooth bores 115 and 116 parallel to and on opposite sides of the internally threaded bore 114. These bores 115 and 116 have anchored therein guide pins 117 and 118, respectively, which are slidably received within suitable bores through a member 119 which also has a central bore 120, through which passes an un-threaded portion of the shank of the feed screw 112.

25 Interposed between the handle 113 of the feed screw and the upper end of the member 119 is a washer 122 and, similarly, a washer 123 is pinned to the screw 112 immediately below the member 119. From the above described construction, it will be seen that as the handle 113 is rotated, the vertical position of the member 119 will be adjusted and at the same time the member 119 is positively retained against rotation relative to the housing 110 as a result of the guide pins 117 and 118, which permit vertical movement of the member 119, but positively preclude any rotational movement of the member 119.

30 The member 119 includes on one lateral side thereof a boss or pad 130 to which is secured a bracket 131 by means of a bolt 132 and, as is seen in Figure 1, this bracket and pad may be provided with a scale 133 in order that the angular position of the bracket 131 with respect to the pad 130 may be accurately adjusted to the predetermined desired position.

35 Secured to the bracket 131 by means of a bolt 135 is a housing 136 which serves to provide means for rotatably mounting a chuck 137 for holding a tap to be ground. This chuck 137 has a rearwardly projecting shank 138 which extends through the housing 136 and has keyed thereto a peripherally notched index disc 139 in order to lock the chuck 137 against relative rotative movement with respect to the housing 136. The notches in the periphery of the index plate are adapted to cooperate with a lug 140, pivotally mounted in the housing by means of a pivot pin 141, and it is seen that this lug 140 is urged toward engagement with the index plate by means of a spring pressed plunger 142. The extreme rear end of the shank 138 of the chuck 137 is provided with a knob 145 by which the chuck may be manually rotated when the lug 140 is withdrawn from engagement with the index plate 139.

40 From the foregoing, it will be apparent that the

lug 140 may be disengaged from the index plate and the chuck holding a tap to be ground may be rotated throughout the desired angular distance between the flutes, and the lug may then be engaged with the corresponding notch in the index plate to lock the chuck against rotative movement while the grinding operation takes place. The index disc 139 may be provided with a sufficiently large number of precisely spaced peripheral notches in order that this assembly 10 will serve to accommodate taps having various numbers of flutes within the range desired.

Bearing in mind the above described structure, the spiral pointing of a tap may be accomplished in the following manner. The grinding wheel 92 first has the peripheral surface thereof trued to provide thereon a radius of curvature approximating the radius of curvature to be ground on the spiral point of the tap undergoing treatment. The tap is then rigidly mounted in the chuck 137, care being taken that the rotative position of the tap with respect to the chuck is such that the flute to be ground will properly be presented to the grinding wheel when the grinding operation commences. The bolt 132 may be loosened, and the bracket 131 is then swung to a position where the angle of engagement of the tap with the grinding wheel will closely approximate the conical angle of the tapered point of the tap.

Inasmuch as the degree of spiral point ground on the tap will be determined by the degree to which the axis of the tap is offset with respect to the plane of rotation of the periphery of the grinding wheel, adjustment of the handle 102 which operates the screw 101 will serve to move the tap axially of the grinding wheel to the predetermined desired position. The handle 113 may then be reciprocated or swung in an arcuate path around the axis of the pin 83, thus bringing the tap point into generally tangential engagement with the periphery of the grinding wheel 92. The magnitude of this movement toward the grinding wheel may be precisely controlled by means of an adjustable stop screw 150 rotatably received in the housing web 97, the inner end of the pin 150 engaging the adjacent surface of the housing 110, thereby limiting inward movement of the tap tangentially of the grinding wheel. As the grinding operation takes place, the amount of grinding to be done may be increased by rotation of the handle 113 which will cause an upward feeding movement of the entire assembly which serves to mount and hold the tap.

When one flute of the tap has thus been ground, the lug 140 may be withdrawn and the chuck holding the tap rotated throughout the desired angular distance to bring the next flute into the predetermined desired position for grinding.

As has been described above, the apparatus at the lefthand side of the assembly, as seen in Figures 1 and 2, serves to grind the land or chamfer back of the cutting edge, and the apparatus at the righthand side of the assembly serves to grind the flute and side wall of the land adjacent the cutting edge.

Inasmuch as the grinding operation just described serves to produce grinding wheel marks on the side wall of the flute which run generally longitudinally of the tap, and inasmuch as such grinding wheel marks tend to interfere to some extent with the removal of chips by the tap during a thread cutting operation, it is generally desirable in the re-conditioning of taps to give these spiral point flutes a slight finishing grind in order that any grinding wheel marks will run in 70

a direction generally perpendicular to the cutting edge in order to facilitate removal of chips by the tap during the cutting operation.

In order to accomplish this last mentioned result, the apparatus includes, as is shown in Figure 5, an electric motor 160, housed within the base 10 of the apparatus. This motor is controlled by means of a suitable switch 161 and has a shaft 162 extending through the front face of the base. To this shaft is anchored a chuck 163 which serves to mount a pencil grinding wheel 164 of relatively small radius. The tap, after having the flutes ground thereon by the apparatus as above described, may have each of the flutes subjected to the action of the pencil wheel 164 to an extent sufficient to obliterate the longitudinal grinding wheel marks formed by the abrasive wheel 92. Inasmuch as this last described operation is more or less of a finishing operation and during it insufficient stock is removed to materially vary the form of the tap point, no apparatus is needed for positioning the tap during this grinding operation. The tap may be held in the hand and merely have one flute after another brought into engagement with the pencil wheel 164 to an extent sufficient to obliterate any longitudinal grinding wheel mark left by the wheel 92.

In grinding the chamfer or relief back of the cutting edge of the tap on that portion of the apparatus shown at the lefthand side of Figures 1 and 2 of the drawings, it will be noted that the tap holder support 35 is provided at the upper side thereof with a projection 170 which serves to mount in adjusted longitudinal position a shaft 171. This shaft 171 may be anchored in predetermined longitudinal position with respect to the housing by means of a set screw 172, and the shaft may have pivoted thereto a locating arm 173 carrying a locating finger 174 adapted to engage the flute between adjacent lands of a tap to be ground. This assembly may conveniently be used if desired when mounting a tap in position in the chuck 52 in order to insure that the relative rotative position of the tap with respect to the chuck is adjusted precisely in the manner desired. After a tap has been thus adjusted in the chuck and anchored firmly in the chuck, the arm 173 may be swung about its pivot so that it will be out of the way during the grinding operation. The set screw 87 is then set in position in one of the holes 86 in order that the angular movement of the tap, caused by swinging movement of the handle 75 in a direction generally arcuately about the axis of the tap, will be limited to the extent necessary, depending upon the number of flutes with which the tap is provided.

The screw 57 is then loosened and the chuck holder adjustably positioned within the bushing 46 with its axis offset from the axis of the bushing 46 to provide the desired magnitude of relief on the land of the tap being ground and, as is clearly apparent from the above described structure, this adjustment must be made in one direction for taps for cutting lefthanded threads, and in the opposite direction for taps for cutting righthanded threads. When this adjustment has been made, the screw 57 is set up to anchor the tap handle in fixed position with respect to the bushing 46 in order that the desired degree of eccentricity between the axes of these two members will be retained throughout the grinding operation.

The nut 33 is then loosened and the entire bracket 32 is swung angularly to bring the tap into a position so that its axis makes the desired

angle with respect to the axis of rotation of the abrasive wheel in order to provide the degree of conical angle required on the point of the tap. The screw 33 is then tightened up in order to anchor the bracket in predetermined adjusted position. The hand nut 36 may be loosened and the entire assembly slid along the bracket to adjust the tap point in position adjacent the periphery of the grinding wheel. The handle 75 is then swung about its pivot 76 in order to withdraw the plunger 69 from the index drum. The index drum is then slid along the shank 65 of the chuck until the particular index disc having the same number of peripheral notches as there are flutes in the tap to be ground lies opposite the inner end of the plunger 69. The handle 75 is then swung to engage the plunger with the corresponding notch.

The motor 12 is then started and, by means of the feed screw 18, the motor may be bodily moved toward the tap to be ground until the periphery of the grinding wheel 20 comes into engagement with the land on which the chamfer is to be produced. As this engagement takes place, the handle 75 is swung generally about the axis of the tap, and it is noted that the angular movement of this handle is limited by the stop pin 85 and the set screw 87, which, as explained above, has been inserted in an aperture so that the angular movement will be controlled in accordance with the movement of flutes on the tap to be ground.

When the desired amount of stock has been removed from the particular land under treatment, the handle 75 may be swung to withdraw the plunger 69 from the index disc and the chuck rotated to bring the next land into position for grinding and the operation repeated.

It will be clear from the foregoing description that the tap re-conditioning apparatus shown in the drawings and described above has been illustrated and described in rather specific detail. Obviously, many modifications, changes, and departures from the above described construction may be made without departing from the generic spirit and scope of the invention as set forth in the subjoined claims.

What is claimed is:

1. In a tap re-conditioning machine for grinding the chamfer on a tap to be ground comprising a chuck housing rotatable about an axis offset from its own axis, a chuck rotatable in said chuck housing, the axis of said chuck coinciding with the axis of said chuck housing, an index drum carried by said chuck, said drum including a plurality of peripheral notches angularly spaced in accordance with the spacing of the flutes on the tap to be ground, and means carried by said chuck housing adapted to engage one of the notches in said index drum to lock said chuck against rotative movement in said chuck housing.

2. A tap holder assembly useful in grinding the chamfer on the point of a tap, including, in combination, a housing having a cylindrical bore therein, a bushing rotatably disposed within said bore and having the axis of its bore coincident with the axis of said first named bore, a tubu-

lar chuck housing disposed within said bushing and spaced from the inner surface thereof, a tap holding chuck adapted to mount axially thereof a tap to be ground mounted within said chuck housing with its axis coincident with the axis of said chuck housing, and adjustable means interconnecting said chuck housing and said bushing for offsetting the axis of said chuck with respect to the axis of said bushing within said space therebetween.

3. A tap holder assembly useful in grinding the chamfer on the point of a tap, including, in combination, a housing having a cylindrical bore therein, a bushing rotatably disposed within said bore and having the axis of its bore coincident with the axis of said first named bore, a tubular chuck housing disposed within said bushing and spaced from the inner surface thereof, a tap holding chuck adapted to mount axially thereof a tap to be ground mounted within said chuck housing with its axis coincident with the axis of said chuck housing, means pivotally connecting said chuck housing and said bushing for swinging movement about said pivot within said space therebetween to offset the axis of said chuck with respect to the axis of said bushing, and means to hold said chuck housing in its offset position.

4. A tap holder assembly useful in grinding the chamfer on the point of a tap, including, in combination, a housing having a cylindrical bore therein, a bushing rotatably disposed within said bore and having the axis of its bore coincident with the axis of said first named bore, a tubular chuck housing disposed within said bushing and spaced from the inner surface thereof, a tap holding chuck adapted to mount axially thereof a tap to be ground rotatably mounted within said chuck housing with its axis coincident with the axis of said chuck housing, and adjustable means interconnecting said chuck housing and said bushing for offsetting the axis of said chuck with respect to the axis of said bushing within said space therebetween.

5. A tap holder assembly useful in grinding the chamfer on the point of a tap, including, in combination, a housing having a cylindrical bore therein, a bushing having a radial flange on one end thereof rotatably disposed within said bore and having the axis of its bore coincident with the axis of said first named bore, a tubular chuck housing having a radial flange on one end thereof disposed within said bushing and spaced from the inner surface thereof, a tap holding chuck adapted to mount axially thereof a tap to be ground mounted within said chuck housing with its axis coincident with the axis of said chuck housing, and means pivotally connecting the flanges of said chuck housing and said bushing for swinging movement of said chuck housing within said space therebetween to offset the axis of said chuck with respect to the axis of said bushing, and means diametrically opposed to said pivot means to hold said chuck housing in its offset position.

SVEN B. HELLSTROM.
